UNITED STATES PATENT OFFICE.

ROBERT S. GRAHAM, OF NEW YORK, N. Y.

KEY FOR TYPE-WRITING AND OTHER MACHINES.

1,218,760.

Specification of Letters Patent. Patented Mar. 13, 1917.

Application filed May 28, 1915. Serial No. 30,970.

To all whom it may concern:

Be it known that I, ROBERT S. GRAHAM, a citizen of the United States and resident of the borough of Manhattan, in the city and State of New York, have invented a new and useful Improvement in Keys for Type-Writing and other Machines, of which the following is a specification.

This invention relates to an improvement 10 in keys for typewriting and other machines, and has for its object to provide a key having a character bearing surface apart from the finger engaging surface, so that when the finger is resting upon the key, the character will still be visible.

Another object is to provide a cushion for the keys having a character bearing surface, formed integral therewith.

Another object is to provide a cushion 20 having a non-slipping finger engaging surface.

Another object is to provide a cushion and character bearing surface which is adapted to be removably secured to keys now in common use.

A practical embodiment of my invention is represented in the accompanying drawings, in which—

Figure 1 represents a plan view of the invention applied to a key,

Fig. 2 represents a side elevation of the same,

Fig. 3 represents a front elevation of the same,

Fig. 4 represents a central section taken in the plane of the line A—A of Fig. 3, and

Fig. 5 represents a side elevation of the invention detached from the key.

This device is particularly well adapted 40 for use upon keys of typewriting and other machines now in common use, where the key stem, denoted by 1, has secured thereto an annular cup 2 having a peripheral rim 3. The head 4 of the cushion has formed integral therewith a character bearing tab 5 which extends downwardly and forwardly from the top edge of the head, thereby placing the character approximately at right angles to the line of vision of the operator 50 as well as placing the character in a position where it will not be obscured by the continual use of the key.

The head 4 has also formed integral therewith a conical base 6, the outer walls of

which converge upwardly to the head 4 so as to form an annular recess 7.

The head 4 is hollowed out to form an air chamber 8 having an opening 9 downwardly through the conical base 6, the walls of which opening diverge to the bottom of the base.

The top or finger engaging surface of the head may be corrugated or roughened, as shown at 10, to give a positive non-slipping surface for the finger of the operator.

The device, consisting of the head 4, the tab 5 and the conical base 6, is made of rubber having a suitable degree of resiliency, so that the conical base 6 may be squeezed into the annular cup 2, with the recess 7 in position to receive the rim 3, while the head forms a yielding cushion for the fingers of the operator.

To prevent the device from turning in the cup 2 while in use, the tab 5 is formed so as to grip the cup 2 between it and the conical base.

Furthermore, the conical base 6 is made a trifle larger in diameter than the inside diameter of the cup 2, so that the base 6 when squeezed into the cup will expand and hold the head and character bearing tab in its proper position on the key. The chamber 8 and its divergent opening 9 when in position in the cup 2 form air chambers which give to the cushion a pneumatic resiliency when pressed by the operator.

It is evident that slight changes may be resorted to in the form, construction and arrangement of the several parts without departing from the spirit and scope of my invention; hence I do not wish to limit myself strictly to the structure herein set forth, but

What I claim is:—

1. In combination with a key having an upwardly open cup-shaped top, a resilient member having a hollow frusto-conical base portion seated within said top and having an upper finger-engaged portion overhanging the rim of said cup, said upper portion having an inner cavity greater in diameter than the upper end of the bore of the said base portion and connected to said bore substantially in alignment with the upper end of said cup-shaped top; the upper end of the latter being larger in internal diameter than the portion of the said base housed thereby, so as to permit a radial expansion

of said top upon pressure on said finger-engaged portion.

2. In combination, a key having a top equipped with an axially vertical ring, and a resilient member having a base portion disposed within said ring and an upper portion projecting above said ring, said base portion being contracted at its upper end

to a diameter smaller than said ring, to permit radial expansion thereof upon a downward pressure on said member.

In testimony, that I claim the foregoing as my invention, I have signed my name this twenty-seventh day of May 1915.

ROBERT S. GRAHAM.
